UNITED STATES PATENT OFFICE.

FREDERICK H. PERRY, OF BEVERLY, MASSACHUSETTS, ASSIGNOR TO UNITED SHOE MACHINERY COMPANY, OF PATERSON, NEW JERSEY, A CORPORATION OF NEW JERSEY.

TRIMMING-MACHINE.

1,030,605.

Specification of Letters Patent. Patented June 25, 1912.

Application filed February 10, 1910. Serial No. 543,071.

To all whom it may concern:

Be it known that I, FREDERICK H. PERRY, a citizen of the United States, residing at Beverly, in the county of Essex and State 5 of Massachusetts, have invented certain Improvements in Trimming-Machines, of which the following description, in connection with the accompanying drawings, is a specification, like reference characters on the drawings indicating like parts in the several figures.

This invention relates to trimming machines.

In particular it relates to a machine for 15 trimming the edge of a boot or shoe sole in the region of the heel breast. A machine of this type is shown in my application Serial No. 395,194 filed September 30, 1907, also assigned to the assignee of the present 20 invention, and the present application is a continuation of the former, so far as the subject matter common to the two cases is concerned.

A general object of this invention is to 25 provide a machine for performing quickly and effectively a trimming operation which has heretofore been performed by hand. In the usual methods of manufacturing shoes the sole edge is trimmed after the heel has 30 been attached to the outsole and has been trimmed and breasted. The forepart of the sole and a part of the shank are then trimmed by an ordinary edge trimming machine, such machine having usually rotary 35 cutters or knives, and the welt or upper edge of the sole is usually beveled or randed at the same time. It is impossible, however, to trim the edge of the shank portion of the sole adjacent to the heel breast on the ordinary edge trimming machine owing to the 40 fact that the heel interferes with the action of the trimming knives; and this part of the sole edge has hitherto been trimmed by hand. In the hand trimming operation the 45 workman usually cuts along the edge of the sole with a suitable knife until the heel breast is reached and he then makes a transverse cut in line with the heel breast to remove the material trimmed from the sole 50 edge.

A particular aim of the present invention therefore, is to provide an improved edge trimming machine which will be particularly adapted for trimming the sole edge in 55 the region of the heel breast.

To this end one feature of the invention consists in the provision of a trimming knife or cutter arranged to trim the edge of the shank of a shoe sole adjacent to the heel breast, preferably in combination with means 60 for positioning the shoe for the operation of said knife or cutter. In the illustrated embodiment of the invention the knife is given a rapid to and fro movement to cause it to cut to the line of the heel breast. In 65 this construction, also, the knife is provided with right and left cutting edges arranged respectively to trim the right and left edges of a shoe sole, and the positioning means not only locates the shoe properly with reference 70 to the knife, but also protects the other parts of the shoe from injury.

Another feature of the invention consists in the provision with means for trimming the edge of a shoe sole adjacent to the heel 75 breast of means for detaching the trimmed material from the sole. In the machine shown herewith the latter means comprises a second knife arranged to cut into the edge of the sole in a direction transverse to the 80 line of cut of the trimming knife, above described, and said second knife preferably cuts to the line of cut of the trimming knife and at the end of the cut made thereby. The means for actuating the knives is arranged 85 to move them alternately to the line of intersection of their paths. In the illustrated embodiment two transversely cutting knives, hereinafter termed "chopping knives", are employed and are arranged to coöperate respectively with the right and left edges of 90 the trimming knife.

The invention also provides novel knives for the purpose just described which may be sharpened conveniently and with the 95 ready adjustment of which sharpening will not interfere. It will be apparent that if the cutting edges of two knives which move transversely to each other are to travel to the same line, the edge of one knife, if this 100 line is curved or inclined, must be curved or inclined transversely to its path of movement, while the edge of the other knife must be curved or inclined in its path of movement. For convenience in adjusting the knives so that the actuating means will move them in such a manner that their cutting edges will travel to the same line, the knives are preferably so constructed that 105 sharpening will affect the relative position 110

of the edge of each knife to its holder along one dimension only of the knife. For the sake of simplicity in construction the edge trimming knife is provided in its preferred 5 form with right and left cutting edges facing in substantially opposite directions and said edges are so shaped as to give to the sole edge the desired transverse contour. To facilitate sharpening of the chopping 10 knives each knife is arc-shaped along its greatest dimension and in cross section is of such form that grinding along a tangent to its inner curve will produce a cutting edge of the desired outline.

15 A further feature of the invention consists in a construction whereby the chopping and trimming knives may be adjusted relatively to each other. It is evident that as the trimming knife is shortened by 20 repeated sharpening its path of travel will be shortened also and its cutting edges therefore will not move to the respective lines of cut of the chopping knives. With a view to compensating for such wear of the trimming 25 knife and the accompanying shortening of its operative stroke and also for the purpose of facilitating accurate initial adjustment of the knives the chopping knives are preferably so mounted that the points 30 of intersection of their paths with the path of the trimming knife may be varied along the path of the latter. Furthermore the chopping knives themselves are secured adjustably in holders so that they may be 35 adjusted transversely of the path of the trimming knife. The knives therefore may be adjusted in such a manner that the co-operating cutting edges will always move to the same line.

40 The invention is also directed to the provision in a machine having an edge trimming knife arranged for to and fro movement of means for limiting the extent of operation of the knife along the sole edge. 45 Preferably, said knife is prevented from trimming beyond the line of the heel breast. In the machine shown in the drawings this result is effected by arranging the chopping knives so that they engage the heel breast 50 and limit the line of cut to the line of the heel breast. Since the chopping and trimming edges cut to the same line the path of cut of the trimming knife also will be limited to the line of the heel breast. The 55 chopping knives thus act as gages for the trimming knife.

The invention also comprises simple and compact means for actuating the knives and other novel features not specifically enumerated above but which will later be described and claimed.

60 In the accompanying drawings,--Figure 1 is a front elevation of a trimming machine constructed according to the present invention; Fig. 2 is a side elevation of the

70 machine; Fig. 3 is a central transverse section through the trimming knife, its holder and guard; Fig. 4 is a perspective view of the heel portion of a shoe showing one side of the sole edge adjacent the heel breast 75 trimmed on the machine of this invention and the other side untrimmed; Fig. 5 is a cross sectional view taken on the line 5-5, Fig. 2; Fig. 6 is a perspective view of the trimming and chopping knives in operative 80 relation to each other; Fig. 7 is a perspective view of a trimming knife; and Fig. 8 is a perspective view of one of the chopping knives.

85 Referring to the drawings, 2 designates a supporting frame provided near its upper end with bearings 4-4 receiving a rotatable shaft 6. The shaft may be driven by means of a belt running over the pulley 8 secured rigidly to the shaft between the 90 bearings 4-4. An angle plate 10 and an arm 12, mounted on a horizontal portion of said plate, are both secured to the forward end of the frame 2 by a bolt 14. A spindle 16 projects rigidly from the vertical depending portion of the angle plate 10 and extends in a direction substantially parallel to the shaft 6 and stationary arm 12. Mounted on the spindle 16 is a rocker frame 18, provided at its rearward end with two depending arms having a slideway formed between them to receive a block 22 mounted on a stud 24 projecting eccentrically from the end of the shaft 6. As the shaft rotates the eccentric stud gyrates the block 22 in the slideway and thus oscillates the rocker frame 18 about the spindle 16. For the purpose of strengthening this portion of the frame a bolt 26 is threaded through the 95 lower ends of the arms and a sleeve 28 is positioned on the bolt between the arms to hold them properly spaced. Lubricating material is supplied to the friction surfaces of the rocker frame and spindle from an oil cup 30 which communicates with a duct 20 formed axially in the spindle 16, the oil flowing out on to the surface of the spindle through ducts 23 spaced along the upper side of the spindle and then back along the lower side of the spindle to small openings 100 25 formed in the rocker frame 18 through which the oil drips on to the block 22. Other ducts, not shown in the drawing, distribute the oil to the friction surfaces of the block and to the surface of the eccentric stud. The rocker frame is provided on its 105 forward end with two laterally extending arms 31 and 32 and a depending arm 34. A knife holder for the edge trimming cutter or knife 36 is formed on the lower end of the arm 34, the arm being split or forked for this purpose. A dove-tailed guideway is 110 formed in the fork members to receive a clamping rib 38 provided on the back of the knife 36 and a bolt 40 extending through the 115 120 125 130

fork members serves to bind them firmly on to the rib 38.

The trimming knife is curved concentrically about the axis of oscillation of the rocker frame 18 and the outer face of the knife is curved transversely to the path of travel of the knife to conform to the transverse contour which it is desired to give to the trimmed portion of the sole edge. This transversely curved form of knife is usually necessary since the cutter of the ordinary edge trimmer usually rounds or bevels the edge of the sole, as indicated at *a*, Fig. 4, and it is desirable, of course, to have the entire shank trimmed to a uniform contour. Right and left cutting edges are formed on opposite ends of the knife 36 each edge being continuous with the outer surface of the knife. Each of the cutting edges consists of a portion designed to trim along the sole edge and another portion indicated at 37, Fig. 7, designed to bevel or round the upper edge of the welt. As the surface of the heel breast is usually curved so that it obliquely intersects the surface of the trimmed sole edge, as indicated in Fig. 4, the cutting edges of the trimming knife are preferably given a slight inclination or slant in their paths of travel, in order to conform to the line of intersection of the heel breast with the sole edge. It will be understood, however, that the shape of the knife edges will be varied to suit different styles and characters of work. By forming the cutting edge of the trimming knife in line with its outer surface, as described, the knife may be sharpened by merely grinding back to the outer surface. Such grinding varies the position of the cutting edge to the body of the knife in one dimension only; or, in other words, grinding shortens the knife but does not change its dimensions in any other respect; and consequently the transverse contour imparted to trimmed surfaces by the knife is not affected by sharpening.

The lateral arms 31 and 32 of the rocker frame carry pivot screws 41 and 42 respectively on which are mounted knife carrying levers 43 and 44. Links 45 and 46 pivoted respectively on the studs 47 and 48 secured in the stationary arm 12 are connected pivotally with the upper ends of the respective levers 43 and 44. Each of the levers has a knife holder formed at its lower end similar in construction to the holder formed on the arm 34 for the knife 36. Left and right chopping knives 51 and 52 respectively are secured in said holders by clamping bolts 53 and 54. The right and left chopping knives are intended to co-operate with the right and left edges of the trimming knife in performing the trimming operation. It should be noted that the centers of the pivot screws 41 and 42 are spaced equally from the center

of oscillation of the rocker frame 18 and that this spacing is equal to the length of the links 45 and 46 between their pivot centers. Each of the levers 43 and 44 therefore forms one side of different parallelograms of motion and as the rocker frame 18 oscillates the operative surface of each of the knives 51 and 52 reciprocates in parallelism with itself. Simultaneously the trimming knife 36 oscillates about the center of oscillation of the frame 18, the reciprocating movements of the trimming knife alternating with those of the chopping knives. Consequently as either edge of the trimming knife cuts along the sole edge the co-operating chopping knife will cut into the sole edge transversely to the cut of the trimming knife.

In order to leave a smoothly trimmed surface and to sever the trimmed material cleanly from the sole, it is necessary to have the chopping knife cut exactly to the line of cut of the trimming knife. To this end the edges of the knives 51 and 52 are curved in their paths of movement to conform to the cutting edges of the trimming knife. Each of the chopping knives is arc-shaped in its greatest dimension and for convenience in obtaining the desired outline of the cutting edge it is shaped in cross section so that the outer edge of its cross sectional outline is like the foreshortened outline of its desired cutting edge. In other words, the cross sectional outline through the peripheral surface of the knife agrees with the projection on a radial plane of the desired cutting edge. By grinding the knife, shaped as shown in Fig. 8, along a tangent to its inner curve (the curve forming the shoulders indicated at *e* and *f*, Fig. 8) a cutting edge of the shape there shown will be obtained, and so long as the grinding is done upon a tangent to this inner curve, the edge will always have the same outline. In this way an edge is obtained on the chopping knife corresponding in outline to the edge of the trimming knife 36 and when the chopping knife is adjusted correctly in its holder its edge will reach at all points to the surface formed by the trimming operation of the knife 36. Each of the chopping knives is provided with a clamping rib 56 by means of which it is secured in its holder and is rendered adjustable transversely of the path of the trimming knife to secure the result just described.

The arc shaped form of the trimming and chopping knives not only produces advantages in sharpening as above described but also has advantages in manufacturing, since the knives may be made by turning a ring of the desired cross sectional form and then cutting the ring into sections of suitable length for the knives. The ribs may then be cut off to the desired dimensions and the

cutting edges formed by grinding as above described.

As the knife 36 is shortened by repeated sharpening its path of travel will be shortened also and it is therefore necessary to provide some means for compensating for such shortening to the end that the coöperating pairs of right and left cutting edges shall always travel to the same line. This object is accomplished in the machine shown by forming an eccentric portion on each of the pivot studs 47 and 48, and pivoting the links 45 and 46 on said portions. Turning the pivot studs on their axes therefore moves the knives 51 and 52 toward or from the ends of the knife 36 and consequently varies the point of intersection of the chopping knives with the path of the trimming knife along the path of the latter. The eccentric pivot studs 47 and 48 are received in split portions of the stationary arm 12 and the arm is provided with screws 57 and 58 which serve to clamp the split portions securely on to the shanks of the studs to hold them in adjusted positions.

For the purpose of protecting the upper of the shoe from injury by the knives and also for the purpose of aiding the operator in positioning the shoe properly with reference thereto, a guard 60 is secured in front of the knives and is provided with a lip 62, Fig. 3, curved over the randing portion of the knife and adapted to enter the crease between the welt and upper of the shoe. The guard is supported by a bracket 64, to which it is secured by a screw 66, and is held in correct position by dowel pins 68, the bracket being mounted in a groove 70 formed in the lower side of the arm 12 and secured therein by a bolt 72.

In the machine illustrated, a rand trimmer of usual construction is mounted on the machine frame, comprising, in the form shown, a rotatable cutter 74 secured to the end of the shaft 76 and a stationary shield 78. This trimmer is here provided for convenience in randing certain portions of the sole edge that cannot be reached by the knife 36, particularly that portion back of the heel breast.

Fig. 1 shows on the left side of the shoe at 6 the portion of the sole edge left untrimmed by the ordinary edge trimmer. To trim this portion of the edge the shoe is presented to the machine in the position indicated at B Fig. 3, the guard lip 62 being forced into the welt crease. As the rocker frame oscillates, the left cutting edge of the knife 36 is forced at each stroke toward the left, 60 into the projecting stock of the sole edge, the knife 51 receding as the trimming knife advances and vice versa. At each stroke of the chopping knife it severs the material trimmed from the sole edge at the previous 65 stroke of the trimming knife. The shoe is

fed past the knives until the chopping knife engages the heel breast and prevents further feeding movement. In this position of the shoe the knife 51 chops into the sole edge in line with the heel breast and to the line corresponding to that indicated on the right edge of the sole at d, Fig. 4. The knife is prevented from chopping beyond this line, since its length of stroke is not sufficient to carry it above the edge of the heel breast. Since the knives are adjusted to cut to the same line, it follows that the trimming knife also will cut to the line corresponding to d, and will be prevented from cutting beyond this line. The trimming of the edge is now complete and the shoe should be presented next to the machine in the position indicated at A Fig. 1 to have the right edge trimmed, this operation being precisely the same as that just described.

It is preferred to use a trimming knife of the double edged form, as shown, because of its simplicity; and it is also preferred to position said knife with its greatest dimension extending substantially horizontal, in the manner shown, since in this position it is more convenient for the workman to present the shoe properly to the operation of the knives and to watch the trimming operation.

Having described my invention, what I claim as new and desire to secure by Letters Patent of the United States is:—

1. In a machine of the class described the combination with means for trimming the edge of a shoe sole to the line of the heel breast, of additional means operating at the same presentation of the shoe to the machine to detach the trimmed material from the sole in a line with said heel breast.

2. In a machine of the class described, the combination with means for trimming the edge of a shoe sole to the line of the heel breast, of means for positioning the shoe for the operation of said trimming means, and means for detaching the trimmed material from the sole edge in a line with said heel breast while the shoe is positioned by said positioning means.

3. In a machine of the class described, the combination with an edge trimming knife arranged to cut along the edge of a shoe sole, of a knife arranged to cut transversely into the edge of the sole at the end of the cut made by the edge trimming knife.

4. In a machine of the class described the combination with an edge trimming knife, of another knife having a cutting movement in a path transverse to that of said edge trimming knife, and means to move said knives alternately to the line of intersection of their paths.

5. In a machine for cutting in shoe shanks, a knife adapted to be moved along the edge of the shank of a shoe toward and away from the heel, and a second knife mov-

able transversely of the path of said first knife.

6. In a machine for cutting in shoe shanks, a knife adapted to be moved along the edge of the shank of a shoe toward and away from the heel, a second knife movable transversely of the path of said first knife, and mechanism for imparting reciprocatory movements to said knives.

10. 7. An edge trimming machine having, in combination, gaging means to determine the position of a shoe, a reciprocating edge trimming knife arranged to cut along the edge of the sole to the breast of the heel, a 15 knife arranged to cut into the edge of the shoe sole in line with the breast of the heel and means for actuating the knives.

8. A shoe sole finishing machine comprising a gage against which the shoe sole is 20 adapted to rest, a reciprocative cross-cut knife arranged to enter said sole at the heel breast, a longitudinally reciprocative planer knife adapted to shave the aforesaid sole edge, and actuating mechanism for both 25 knives.

9. In a machine of the class described, the combination with means for trimming the edge of a shoe sole to the line of the heel breast and means for positioning the shoe 30 for the operation of said trimming means, of means for randing the upper edge of said sole, and means for detaching the material severed from the sole by the randing and trimming means in the line of said heel breast, said positioning means serving also 35 to position the shoe for the operation of said randing and detaching means.

10. In a machine of the class described, the combination with means for randing 40 the upper edge of a shoe sole to the line of the heel breast, and means for positioning the shoe for the operation of said randing means, of means operating while the shoe is positioned by said positioning means to detach the material severed from the sole by the randing means in the line of said heel breast.

11. In an edge trimming machine the combination with an edge trimming knife arranged to cut along the edge of a shoe sole, said knife being so shaped that it effects a rounding of the outer edge of the sole and a beveling or randing of the upper edge of the sole, of a knife shaped and arranged to 50 cut transversely into the edge of the sole at the end of the cut made by the edge trimming knife and only to the surface trimmed by said edge trimming knife.

12. In an edge trimming machine the 60 combination with an edge trimming knife arranged to cut along the edge of a shoe sole, said edge trimming knife being shaped to give to the sole edge a predetermined transverse contour, of a knife arranged to 65 cut transversely into the edge of the sole at

the end of the cut made by the edge trimming knife, and means for actuating said knives, said second knife being so shaped and moved that at the end of its operative movement it contacts with the trimmed surface of the sole edge along the entire line of intersection of the path of said second knife with the path of said edge trimming knife.

13. In an edge trimming machine the combination with an edge trimming knife 70 having portions adapted to operate upon the upper side of the sole, of means to actuate said knife to effect a trimming operation along the sole edge to the breast of the heel, a second knife having an edge the contour 80 of which corresponds to the transverse contour of the trimmed sole edge, and means for moving said second knife transversely to the path of movement of the edge trimming knife to sever the trimmed material 85 adjacent the heel breast.

14. In an edge trimming machine the combination with a rocking frame and means for rocking said frame, of an edge trimming knife rigidly attached to said frame, a second knife pivotally mounted upon said frame and connections between said second knife and a stationary part arranged to cause said knife to move transversely to the path of movement of the edge 90 trimming knife.

15. An edge trimming machine comprising, in combination, a cutter having a plurality of cutting edges arranged to trim the edges of shoe soles and means for detaching 100 the material trimmed from the sole by said edges.

16. An edge trimming machine comprising, in combination, a cutter having two cutting edges, means for imparting to and fro movements to said cutter and additional cutters coöperating with said cutting edges at the ends of their operative movements.

17. An edge trimming machine comprising, in combination, a knife having two cutting edges arranged to have different cutting movements and a pair of knives each arranged for movement in a path transverse to the path of the first knife.

18. An edge trimming machine comprising, in combination, a knife having two cutting edges facing in substantially opposite directions and arranged for to and fro movements, a pair of knives each arranged for movement in a path transverse to the 115 path of the first knife and common means for actuating said knives.

19. An edge trimming machine comprising, in combination, a double-edged trimming knife arranged to cut along the edge 125 of a shoe sole and two independent knives arranged respectively to cut transversely into the edge of the sole at the ends of the cuts made by the edges of said trimming knife.

20. An edge trimming machine comprising, in combination, a knife having right and left cutting edges arranged for different cutting movements, said knife being constructed and arranged to trim the edge of a sole shank to the line of the heel breast, and means for detaching the trimmed material from the sole in a line with said heel breast.
21. An edge trimming machine comprising a trimming knife having right and left edges, right and left chopping knives co-operating respectively with said right and left edges, said chopping knives each being arranged to move in a path transverse to that of its coöperating trimming edge and means for moving said trimming knife to cause its edges to move alternately to their respective lines of intersection with the paths of the chopping knives.
22. An edge trimming machine comprising, in combination, a double-edged trimming knife arranged to cut along the edge of a shoe sole, the edges of said knife being shaped to give to the sole edge a predetermined transverse contour, two chopping knives arranged respectively to cut transversely into the edge of the sole at the ends of the cuts made by the edges of said trimming knives, means for actuating said knives, each of said chopping knives being so shaped that at the end of its operative movement it contacts with the trimmed surface of the sole edge along the entire line of intersection of the path of said chopping knife with the path of the edge trimming knife.
23. In an edge trimming machine, the combination of a cutter constructed and arranged to trim the edge of a shoe sole shank in front of and up to the heel breast, means for protecting the heel from the action of said cutter but permitting said cutter to trim substantially to the heel breast, and means for positioning the shoe for the operation of said cutter.
24. In an edge trimming machine the combination with an edge trimming knife arranged to move in a predetermined path of predetermined extent, of means for positioning a shoe with respect to said knife so that said knife will move in its trimming operation only to the heel breast of said shoe.
25. In an edge trimming machine the combination with an edge trimming cutter arranged to trim the shank portion of a sole edge to the line of the heel breast, of means for preventing said cutter from trimming beyond said line.
26. In an edge trimming machine the combination with an edge trimming cutter adapted to trim the shank portion of a sole edge to the line of the heel breast, of means for limiting the extent of cut of said cutter along the sole edge and means for limiting the depth of cut of said cutter.
27. In an edge trimming machine the combination with an edge trimming cutter adapted to trim the shank portion of a sole edge to the line of the heel breast, of a gage arranged to enter the crease between the shoe upper and the sole and a second gage arranged to engage the heel of the shoe being trimmed.
28. In an edge trimming machine the combination with an edge trimming knife arranged to cut along the edge of a shoe sole, of a knife arranged to cut transversely into the edge of the sole at the end of the cut made by the edge trimming knife, and means to position the work for the operation of said knives.
29. In a machine for cutting in shoe shanks, a knife adapted to be moved along the edge of the shank of a shoe toward and away from the heel, a second knife movable transversely of the path of said first knife, and a rest against which said shoe may be placed.
30. In a trimming machine the combination with means for trimming the edge of a shoe sole, of means for detaching the trimmed material from the sole and means for limiting the extent of operation of the trimming means along the sole edge.
31. In a trimming machine the combination with means for trimming the edge of a shoe sole, of a single means for detaching the trimmed material from the sole and for limiting the extent of cut of the trimming means along the sole edge.
32. In a trimming machine the combination with means for trimming the edge of a shoe sole, of a single means for detaching the trimmed material from the sole in a line with the heel breast and for preventing said trimming means from trimming beyond the line of said heel breast.
33. In a trimming machine the combination of a cutter arranged to trim the edge of the shank portion of the shoe sole, a second cutter movable transversely to the path of the first cutter, said second cutter being arranged to engage the heel breast of the shoe and thereby limit the extent of cut of the first cutter along the sole edge.
34. In a trimming machine the combination of an edge trimming cutter arranged to trim the edge of a shoe sole adjacent the heel breast, a second cutter arranged to cut transversely into the edge of the sole at the end of the cut made by the trimming cutter, said second cutter being arranged for engagement with the heel to prevent the trimming cutter from operating beyond the line of the heel breast.
35. In a trimming machine the combination with means for trimming the edge of a

shoe sole, of a single means for detaching the trimmed material from the sole and for limiting the extent of cut of the trimming means along the sole edge and means for positioning the shoe for the operation of said trimming and detaching means.

36. In an edge trimming machine the combination with an edge trimming knife arranged to cut along the edge of a shoe sole and having a portion adapted to rand the sole simultaneously with the edge trimming operation, of a knife arranged to cut transversely into the edge of the sole at the end of the cut made by the edge trimming knife, and means to guard the upper against the action of said knives.

37. An edge trimming machine having, in combination, an edge trimming cutter arranged to trim the edge of a shoe sole to the breast of the heel, a cutter arranged to cut into the edge of the sole in line with the breast of the heel and means to position the shoe properly with relation to said cutters.

38. A sole edge trimming machine comprising, in combination, a pair of spaced chopping knives arranged to reciprocate in substantially parallel paths, a trimming knife having two cutting edges arranged one adjacent each of said chopping knives, means for moving said trimming knife transversely to said paths, and a guard arranged to protect the shoe upper from the action of said knives.

39. An edge trimming machine comprising, in combination, a double-edged trimming knife adapted to trim the edge of a shoe sole, two knives arranged respectively to cut transversely into the edge of the sole at the ends of the cuts made by the edges of said trimming knife, and means for positioning the shoe for the operation of said knives.

40. A machine for trimming the sole edge of a shoe shank, comprising in combination, a trimming knife having right and left cutting edges, coöperating right and left chopping knives arranged respectively to move in paths transverse to the paths of said right and left edges, means for imparting reciprocating movements to all of said knives, each of the chopping knives being arranged to engage a heel breast and thereby limit the extent of cut of said trimming knife along a sole edge.

41. A machine for trimming the shank portion of a sole edge comprising a trimming knife having right and left cutting edges arranged for cutting movements in different directions, right and left chopping knives coöperating respectively with said edges and arranged to cut transversely into the sole edge at the ends of the cuts made by said trimming edges, each of said chopping knives being arranged to engage the heel and thereby prevent said knives from

cutting beyond the line of the heel breast and a guard for protecting the upper from the operation of said knives.

42. An edge trimming machine comprising, in combination, an edge trimming cutter and a cutter movable in a path transverse to that of the edge trimming cutter, said cutters being relatively adjustable so that the position of the line of intersection of their paths may be varied.

43. An edge trimming machine comprising, in combination, an edge trimming knife and a knife movable in a path transverse to that of the edge trimming knife, one of said knives being adjustable to vary the point of intersection of the paths of said knives along the path of travel of the other knife.

44. An edge trimming machine comprising, in combination, an edge trimming knife, a second knife movable in a path transverse to the path of the edge trimming knife and means whereby the second knife may be adjusted to vary its point of intersection with the path of the edge trimming knife along the path of said trimming knife.

45. An edge trimming machine comprising, in combination, an edge trimming knife arranged for to and fro movement, a second knife movable in a path transverse to that of the trimming knife, said second knife being arranged for adjustment both longitudinally and transversely of the path of the trimming knife.

46. An edge trimming machine comprising, in combination, an edge trimming cutter arranged for to and from movement, a second cutter movable in a path transverse to that of the trimming cutter and a holder for each of said cutters in which the cutters are adjustably secured.

47. An edge trimming machine comprising, in combination, an edge trimming knife arranged to cut along the edge of a shoe sole, a knife arranged to cut transversely into the edge of said sole, a holder for each of said knives and means whereby one of said holders may be adjusted to move in different paths all substantially parallel to each other.

48. An edge trimming machine comprising, in combination, a rocking frame, means for rocking said frame, an edge trimming knife rigidly secured to said frame, a knife holder pivotally connected with said frame, a second knife carried by said holder, a connection between a stationary part of the machine and said holder arranged to cause said second knife to move transversely to the path of movement of the edge trimming knife, said connection including an adjustment whereby the path of movement of the second knife may be varied.

49. An edge trimming machine comprising, in combination, a trimming knife having two cutting edges arranged for differ-

ent cutting movements, two chopping knives arranged one adjacent each of said cutting edges, each of said chopping knives being movable in a path transverse to that of the 5 trimming knife and means whereby the chopping knives may be adjusted toward or from the edges of the trimming knife.

50. An edge trimming machine comprising, in combination, a rocker frame having 10 a depending arm and two lateral arms, a holder formed at the lower end of said depending arm, a double-edged trimming knife rigidly secured in said holder, a lever connected to each of said lateral arms, 15 a knife holder formed on the lower end of each lever adjacent the respective edges of said knife, a chopping knife secured in each of said holders, and a link connecting the other end of each lever with a stationary 20 part of the machine whereby said chopping knives are caused to move in paths transverse to that of the trimming knife.

51. An edge trimming machine comprising, in combination a rocker frame having 25 a depending arm and two lateral arms, means for imparting an oscillatory motion to said frame, a trimming knife adjustably secured at the lower end of said depending arm, said knife having two edges facing in 30 substantially opposite directions, a pair of knife holders pivotally connected respectively to said lateral arms, a chopping knife adjustably secured in each of said holders, an adjustable link connection between each 35 of said holders and a stationary part of the machine and a guard secured in front of said knives.

52. In an edge trimming machine a trimming cutter curved along its greatest dimension, said cutter having a cutting edge 40 formed at each end thereof, each of said edges being in a line with the outer surface of said cutter, said surface being shaped to give the sole edge the desired transverse contour and 45 a rib on the back of said cutter whereby it may be secured in a suitable holder.

53. In an edge trimming machine a knife, arc-shaped along its greatest dimension, having the outer part of its cross sectional 50 outline like the foreshortened outline of its desired cutting edge, and ground to an edge along a tangent to its inner curve.

54. In a sole edge trimming machine a cutter having a surface conforming in transverse contour to that which it is desired to give to a sole edge, said cutter having right and left cutting edges formed thereon by grinding opposite ends of the cutter back to 55 said surface and means for giving said cutter rapid to and fro movements in the direction of its length.

55. An edge trimming machine comprising, in combination a cutter provided with a cutting edge having one portion arranged to 60 trim along a sole edge and another portion

arranged to bevel the upper edge of the sole and means for imparting rapid to and fro movements to said cutter in a fixed path.

56. A machine for trimming that portion of the sole edge between the heel breast and the point in the shank at which the usual machine trimming operation is stopped, comprising a cutter having an edge shaped to give to the sole edge a transverse contour like that of the previously trimmed portion 70 of the sole edge and means for giving said cutter rapid to and fro movements in a fixed path.

57. An edge trimming machine comprising a cutter arranged to complete the trimming of the shank portion of a sole edge adjacent to the heel breast, said cutter having a cutting edge shaped to give to the sole 80 edge a transverse contour conforming to that of the previously trimmed portion of 85 the sole edge.

58. An edge trimming machine comprising a cutter arranged to complete the trimming of the shank portion of a sole edge adjacent to the heel breast, said cutter having 90 a cutting edge shaped to give to the sole edge a transverse contour conforming to that of the previously trimmed portion of the sole edge, and means for positioning the shoe for the operation of said cutter. 95

59. An edge trimming machine comprising in combination an edge trimming knife arranged to cut along the edge of a shoe sole, a second knife arranged to cut transversely into the edge of said sole and means 100 whereby one of said knives may be adjusted to move in different paths all substantially parallel to each other.

60. In a trimming machine, the combination of a cutter arranged to trim that portion of the sole edge between the heel breast and the point in the shank at which the usual machine trimming operation is stopped, means for driving the cutter, and 105 means for protecting the other parts of the shoe during the trimming operation from injury by said cutter, but permitting the cutter to trim to the heel breast. 110

61. In a trimming machine, the combination of a cutter constructed and shaped to trim the edge of a shoe sole in front of and substantially to the heel breast and means for protecting the heel from contact with 115 said cutter but permitting the cutter to trim substantially to the heel breast. 120

62. In a trimming machine, the combination of a cutter constructed and shaped to trim the edge of a shoe sole in front of and to the heel breast, means for moving said cutter to do its work and a device arranged to engage the heel breast to protect the heel from contact with said cutter, said device being so arranged with reference to the cutter that it permits the cutter to trim the sole edge substantially to the heel breast. 125

63. In a trimming machine, the combination of a cutter mounted for movement about an axis and constructed and shaped to trim that portion of the sole edge between the heel breast and the point in the shank at which the usual machine trimming operation is stopped, means for driving the cutter, and means co-operatively arranged with reference to the cutter to protect the heel from contact therewith during the trimming operation while permitting the cutter to trim substantially to the heel breast.

64. In a trimming machine, the combination of trimming means arranged to trim the edge of a shoe sole in front of and to the line of the heel breast and means for preventing the trimming means from trimming beyond said line but constructed to permit such relative movement of the shoe sole and trimming means that the sole edge will be trimmed substantially to the line of the heel breast.

65. In a trimming machine, the combination of trimming means arranged to trim the edge of a shoe sole in front of and to the line of the heel breast, means for protecting the heel from the action of said trimming means constructed to permit said trimming means to trim substantially up to said line and additional means for protecting other parts of the shoe from the action of said trimming means.

66. In a trimming machine, the combination of trimming means arranged to trim the edge of a shoe sole in front of and to the heel breast, means for protecting the heel from injury by said edge trimming means but constructed to permit said edge trimming means to trim substantially to the heel breast and additional means for engaging the shoe sole to aid in positioning the shoe properly during said trimming operation.

67. In a machine of the class described, the combination of trimming means arranged to trim the edge of a shoe sole in front of the heel breast, means for protecting the heel breast from the action of said trimming means constructed to permit said edge trimming means to trim the sole edge substantially to the line of the heel breast and means for protecting the upper of the shoe, adjacent to the sole edge acted upon, from the action of the trimming means.

68. In a machine of the class described, the combination of trimming means arranged to cut down the sole edge of a shoe in front of the heel breast to a point below the edge surface of the heel and substantially to the plane of the heel breast, means for protecting the heel from the action of the trimming means constructed to permit said trimming means to trim the sole edge substantially to the plane of the heel breast and means for protecting the upper of the

shoe, adjacent to that portion of the sole edge acted upon, from the action of said trimming means.

69. A machine of the class described, having in combination, an edge trimming knife constructed and arranged to trim the edge of the shank of a shoe sole from the point where the rotary trimming began, or left off, to the breast of the heel and a second knife arranged to move transversely to the path of movement of the edge trimming knife at the end of the cutting stroke of said edge trimming knife.

70. A machine of the character set forth having, in combination, means for trimming the edge of the sole longitudinally thereof to the breast of the heel, means for cutting transversely of said sole to cut off the material thus trimmed in line with the breast of the heel, means for randing the upper edge of the sole, and a crease gage arranged to bear against the upper face of said sole, whereby said sole is positioned laterally thereof relatively to said trimming, cutting and randing instrumentalities.

71. A machine of the character set forth having, in combination, means for trimming the edge of the sole to the breast of the heel, means for cutting off the material thus trimmed in line with the breast of the heel, means for randing the upper edge of the sole, and a crease gage arranged to bear against the upper edge of the sole, whereby said sole is positioned laterally thereof relatively to said trimming and randing instrumentalities.

72. In a machine of the class described, the combination of means for cutting down the edge of a shoe sole in front of and to the line of the heel breast, and a gage so positioned with reference to said means that it protects the heel breast from contact therewith, said gage being shaped and arranged to permit said means to operate on the sole edge substantially to the line of the heel breast.

73. In a machine of the class described, the combination of means constructed and shaped to cut down the edge of a shoe sole in front of the heel breast to a point below the edge surface of the heel and substantially to the plane of the heel breast, a gage so located with reference to said means that it engages the heel breast and prevents the heel from coming into contact with said means, said gage being shaped and arranged to permit said means to operate on the sole edge to substantially the line of the heel breast and a guard for protecting the upper of the shoe adjacent to the point of operation of said means from contact therewith.

74. In a machine of the class described, a knife for cutting to a given curved or irregular line, said knife having a face agreeing in cross sectional outline with the projection

of the desired cutting edge on a plane normal to the greatest dimension of the knife but being ground along a predetermined plane intersecting said face at such an angle that a cutting edge like said given line is produced.

75. In a machine of the class described, a knife for cutting to a given curved or irregular line, said knife having a face agreeing in cross sectional outline with the projection of the desired cutting edge on a plane normal to the greatest dimension of the knife

and being ground along the plane, intersecting said face, in which said given line will lie at the end of the cutting stroke of the knife.

In testimony whereof I have signed my name to this specification in the presence of two subscribing witnesses.

FREDERICK H. PERRY.
